METHOD OF PRODUCING A PULLING STRESS
AND HYDRAULIC PULLING MECHANISM

Siegmund Mandl and Edward M. Pfauser, Milwaukee, Wis., assignors to Blackhawk Mfg. Co., Milwaukee, Wis., a corporation of Wisconsin

Application March 16, 1935, Serial No. 11,514

24 Claims. (Cl. 153—32)

This invention relates to hydraulic pulling mechanisms, and more particularly is directed to a pulling mechanism whereby hydraulic force is applied in controlled quantities to displace or deform metal frame members, specifically for bending and straightening such members.

Heretofore, the application of hydraulic pressure for such operations has been extremely difficult, due to the impracticability of positioning the hydraulic pressure-applying unit in a location such that the full effective force developed by the unit can be utilized for the pulling operation. Bending and twisting stresses incident to the development of a hydraulic pressure in devices heretofore employed have been transmitted directly to the unit, tending to make its positioning both precarious and dangerous to the operator. Further, in operations of this type, spacial limitations prevent the proper use of hydraulic jack units of the type now employed in garages, repair shops and similar establishments.

We have found that in order to secure the most advantageous application of hydraulic pressure it is distinctly desirable to dissociate the pressure applying or pulling mechanism from the source of pressure supply, or pump unit. This feature has been brought out in suitable detail in the copending application of Edward M. Pfauser, Serial No. 4,728, filed February 4, 1935, in which the provision of a metal straightening machine including a power unit of general utility for the application of hydraulic force to the straightening or bending of metal members is disclosed.

The present invention contemplates the provision of a pulling mechanism wherein the entire available hydraulic pressure may be utilized for the pulling operation, and no portion of this force need be dissipated in maintaining the mechanism in position, or in absorbing and overcoming the bending and twisting stresses developed at the pump unit. In furtherance of this concept, we provide a pulling mechanism which is adapted to be expanded hydraulically for straightening or bending a metal member, or for drawing two such members toward each other. The invention also contemplates a mechanism which will aline itself axially in the direction in which the force is to be applied, so that the maximum effective force may be utilized in the bending or straightening operation.

The use of hydraulic pressure to draw two members toward each other, or to straighten or bend one member toward a fixed support, has not,

to our knowledge, heretofore been incorporated in a mechanism employing a portable ram or power unit dissociated from the pressure supply or pump unit. In the present invention, the ram unit comprises a pressure cylinder and an axially reciprocating plunger mounted therein and movable in response to fluid pressure manually developed and controlled by a pump unit disposed at a remote point, the pressure being transmitted to the power unit through a flexible conduit that prevents the transmission of stresses from the pressure developing unit to the power applying unit. As disclosed fully in the Pfauser application aforesaid, the ram unit is operable in any desired angular position and is thus all-directional in use.

Further, the particular manner of connecting the power unit for operation provided by the present invention possesses certain distinct advantages not heretofore obtainable. The mechanism is capable of alining itself automatically into operative position, and permits the pulling force to be exerted in a direction such that maximum pulling effect per unit of force applied is produced.

Another feature of our invention, which is of distinct advantage, is the provision of adjustable coupling means whereby the mechanism is capable of adjustment in accordance with the spacing between the two members between which relative movement is to be effected, in order to accommodate the mechanism to various spacing between such members. In addition, we preferably provide a link or chain connection of the mechanism to the members, so that the pulling effort is exerted through non-rigid means, and thus the direction of pull is preferably at all times along a line extending substantially normal to the plane of the member being pulled, which is distinctly advantageous in applying force for this purpose.

In order to provide means for rapid and simplified connection of the pulling mechanism in operative position, we provide, in the present invention, a novel type of chain-pull plate, one of the plates being preferably secured to the base or fixed end of the power unit, while the second plate, of similar design, is secured to the projecting end of the power plunger. Thus, upon extension of the plunger due to the application of hydraulic pressure to the power unit, the plates are moved away from each other, providing a commensurate pulling force between the members about which the chains have been secured.

We have found that in straightening of metal members frequent sighting or measurement of the deflection of the members is desirable, in order to secure accurate bending or straightening thereof. By the provision of a graduated plunger in the power unit, we are able to secure a positive indication of the deflection of the member being bent or straightened, and can thus determine to a quite accurate degree the exact amount of pressure which is applicable for predetermined displacement of the metal. This allows the operator to judge the deflection of the member without the necessity of auxiliary sighting apparatus, and prevents overstressing of the metal, or bending of the member to an extent greater than that desired.

The present invention is of relatively simple mechanical design, employing a small number of parts, and is capable of rapid connection into and disconnection from its operating position, whereby its use in garages, repair shops and similar establishments is of distinct practical advantage.

Other objects and advantages secured by the present invention will be described in detail in connection with the following specification, which, taken in connection with the accompanying drawings, will disclose to those skilled in the art the particular construction and operation of a preferred form of our invention.

In the drawings:

Figure 1 is a perspective view of the pulling mechanism of the present invention employed in a straightening operation;

Figure 2 is an elevational view, partly in section, of the pulling mechanism shown in Figure 1;

Figure 3 is a perspective view showing a modified form of the invention, employed for pulling two members toward each other to straighten or bend the same;

Figure 4 is a plan view of one of the chain-pull plates shown in Figure 3;

Figure 5 is a sectional view, taken substantially on line 5—5 of Figure 4, showing in detail the construction of the pull plates;

Figure 6 is a perspective view showing a somewhat modified pulling mechanism embodying the present invention;

Figure 7 is a top plan view of one of the chain-pull plates shown in Figure 6; and

Figure 8 is a sectional view taken on line 8—8 of Figure 7.

Referring now in detail to the drawings, in Figure 1 we have disclosed the application of our hydraulic pulling mechanism to the straightening of a front axle assembly of an automotive vehicle.

The front axle is indicated at 5, and is provided with rearwardly extending radius rods 6 forming a substantially V-shaped structure. The axle 5, in this embodiment of the invention is shown as being bent outwardly, and the mechanism which we have provided is for the purpose of pulling the axle 5 inwardly toward the joined ends of the radius rods 6.

The pulling unit, as shown more particularly in Figure 2, comprises a hydraulic ram unit 7 having a base portion 8 and an axially extensible plunger 9, the ram unit being of the type described in detail in the above-identified copending application of Edward M. Pfauser.

The base 8 of the ram 7 is provided with a threaded recess adapted to receive a coupling member 10 threaded thereinto, and having bear-

ing engagement within a pressure plate 12 secured thereto. A pair of yoke rods 13 are secured at one end in suitable opposed openings in the plate 12, and are prevented from axial displacement out of these openings by means of nuts 14 threaded onto the ends of the rods.

The plunger 9 of the ram unit has a threaded head portion 15 extending into a suitable pull plate 16 having opposed openings receiving the rods 13, the pull plate 16 being adapted for sliding movement longitudinally of the rods.

The rods 13 are extended outwardly of the pull plate 16 for any desired distance, and adjacent their outer projecting ends are provided with a second pull plate 17, of the same general form as the pull plate 16, which is mounted for movement on the rods 13 by means of opposed openings formed therein, the plate 17 being prevented from displacement outwardly of the rods by means of a pair of nut members 18 threaded onto the projecting ends of the rods.

The ram unit 7 comprises a ram cylinder adapted to receive fluid under pressure from a flexible fluid pressure transmitting conduit 20 coupled as at 22 to the base 8 of the ram unit. This coupling provides communication between the hose 20 and the interior of the ram cylinder. The flexible conduit 20 at its opposite end, is coupled to the outlet port 23 of a pump unit 24, the pump unit 24 being of the type disclosed in detail in the above-mentioned copending application of Edward M. Pfauser.

The pump member comprises a pump cylinder or reservoir containing the fluid to be placed under pressure, and a rocking beam 25 adapted to be rocked about pivot 26 by means of an actuating lever 27 to produce reciprocation of the pressure plunger within the head end 28 of the pump unit, thereby drawing fluid from the reservoir of the pump unit and transmitting it under pressure to the conduit 20 through the outlet port 23. The pump unit 24 is provided with a laterally projecting foot portion 29 at its forward end, adapted to be engaged by the foot of an operator, and a clamping member 30 at its rearward end 45 having an upwardly disposed foot portion 32 adapted to be engaged by the opposite foot of the operator, whereby the pump unit may be maintained in fixed position on the floor during reciprocation of the operating handle 27.

The present invention is not concerned primarily with the details of the pump construction, and reference may be made to the above-mentioned copending application for a fuller explanation of the operation thereof.

The ram unit 7, as shown in Figure 1, is disposed within the triangular structure formed by the axle 5 and the radius rods 6, and the plate 16 is provided with opposed chain latching portions adapted to receive the opposite ends 34 and 35 of a chain member which, at its intermediate portion, is wrapped around the juncture 36 of the radius rods. The ends 34 and 35 of the chain may be adjustably secured in fixed locked position upon the plate 16, whereby actuation of the plunger 9 due to fluid pressure within the ram cylinder results in movement of the plate 16 outwardly along the rods 13, thereby placing tension upon the chain between its fixed clamped ends 34 and 35 and the portions 36 thereof. Similarly, the plate member 17 is provided with chain gripping portions 37, receiving the ends 38 and 39 of a second chain member 40, wrapped at its intermediate portion about the center of the axle 5, as shown at 42.

It is apparent, therefore, that upon reciprocation of the actuating handle 27 of the pump unit 24, fluid under pressure will be transmitted therefrom through the conduit 20 to the ram cylinder 7, causing outward movement of the plunger 9, or movement to the right, as viewed in Figure 2. This movement is resisted by the connection of the plate 17 to the axle 5 through the tension chain 40, whereby the plate 17 tends to move to the left, as shown by the arrow in Figure 2. This results in the plates 16 and 17 having relative movement toward each other when pressure is applied to the ram unit, which results in shortening the distance between the portions 36 and 42 of the chains, and producing a pulling tension upon the axle 5 tending to bend and/or straighten the same.

The plunger 9 is preferably provided with graduated indications, as shown in Figure 2, and the operator, standing at the pump unit 24, can actuate the pump 27 and thus control the amount of pressure transmitted to the unit 7. At the same time, by noting the graduations on the plunger 9, any predetermined deflection of the axle or other member 5 can be produced. Thus, if the operator has ascertained that a deflection of two inches of the center of the axle 5 with respect to its former position is desirable, he may actuate the pump unit 24 to produce a corresponding movement of the plunger 9, indicated by the graduations thereon, whereby the deflection of the member 5 may be accurately controlled. Further, it is to be noted that the development of pressure at the pump unit 24, which produces stresses at the pump unit, will not act to transmit these stresses to the ram unit 7, inasmuch as the flexible conduit 20 is interposed therebetween. This conduit 20 is preferably formed of a suitable metal reenforced cable provided with a rubber or other resilient body portion.

Referring now to the structure shown in Figure 3, the ram unit 7 of this embodiment of the invention has its base 8 provided with a suitable coupling member to which a chain pull plate 48 is directly secured. At its opposite end, the ram plunger 9 is threaded into a depending socket portion 50 of a second chain pull plate 52 shown in detail in Figures 4 and 5. The two plates 48 and 52 are substantially identical in design, and correspond to plates 16 and 17 of the embodiment shown in Figure 1.

Considering now Figures 4 and 5 in detail, the pull plate 52 is provided with a plurality of radially extending tongue portions, one pair of tongue portions 53 being provided with openings 54 adapted to provide guiding means for chain members, such as the chain members 55 and 56 of Figure 3, therethrough.

Extending at right angles to the opposed tongues 53 are a pair of diametrically opposed lug members 57, which members are provided, at their ends, with inturned spaced edges 58 defining slots 59 extending radially inwardly toward the center of the plate. Suitable web portions 60 are formed centrally of the members 57, and extend to the defining edges of the slot 59, forming recessed slotted sockets adapted to secure chain links therein. As shown in Figure 3, a link member is adapted to slide laterally into the slot 59, and the adjacent link members then have abutting engagement against the web portions 60 for limiting movement of the chain member with respect to the plate.

The plate 52 is internally threaded within the

socket projection 50 to receive the threaded end 15 of the ram plunger 9, and above this portion is an annular recess 62 forming a slight clearance for threading of the ram plunger 9 into and out of the plate. Above the recess 62 the plate 52 is provided with a central cylindrical bore 63 extending to the outer surface of the other side of the plate, and providing a socket for receiving a drift pin 64 or the like, employed for punching or pressing out wrist pins, bearings and the like. A suitable threaded radially extending opening 65 is provided between two of the extending leg portions of the plate 52, and extends into the cylindrical opening 63. The opening 65 is adapted to receive a suitable set screw 66 which is threaded thereinto to have bearing engagement against the surface of a pin such as the pin 64, to secure and hold the pin in fixed position with respect to the plate, preventing its displacement from the plate when the plate is reversed in position.

In the production of pulling force between two members, such as the members 72 and 73 of Figure 3, which may be spaced members adapted to be pulled together, or may comprise a fixed supporting member and a second member which is to be bent or straightened, or pulled toward the supporting member, the ram unit 7 is disposed between the members 72 and 73, and the plates 48 and 52 are secured to the base 8 of the unit and to the plunger 9 thereof, respectively. The chains 55 and 56 are then secured in the position shown, the chain 55 being wrapped about the member 73, having its ends guided for movement in the openings 54 of the plate 48, and then extending along the ram unit on opposite sides thereof and being locked in fixed position within the slots 59 of the plate 52. The chain 56, on the other hand, has its intermediate portion wrapped around the member 72, and the ends thereof are extended through the guide openings 54 of the plate 52, and are locked in fixed position in the slots 59 of the plate 48. Upon the application of pressure to the interior of the ram cylinder, the plunger 9 is moved axially outwardly of the cylinder, tending to move the plates 48 and 52 apart. Since the overlapping ends of the opposite chains are secured to these plates, this produces a tension stress upon each of the chains, tending either to draw members 72 and 73 toward each other, or to draw either one of these members towards the other, if the other member is a fixed support.

It will be noted that there is no structure which prevents the independent movement of the ram unit 7 when connected in this manner, and it is therefore apparent that upon the initial application of pressure to the unit, the unit will assume a position such that its axis lies in a line corresponding to the direction of pull between the members 72 and 73, whereby a straight line tension pull is exerted between these members. This is of material advantage in providing for maximum exertion of pulling force by the unit in accordance with the pressure applied thereto.

Inasmuch as the slots 59 of the two pull plates 65 are adapted to receive any of the links of the chain members, these chain members may be readily adjusted to the desired lengths necessary for proper spacing of the ram unit 7 between the members 72 and 73. If desired, a suitable extension may be secured to the end of the plunger 9, and the plate 52 may be secured to this extension, thereby elongating the ram unit 7, if the spacing of the members 72 and 73 is such as to require such extension. However, ordinarily the lengths of 75

the chains can be varied sufficiently to provide for operation of the ram unit within any desired spacing of members to be bent or straightened.

Referring now in more detail to the structure shown in Figures 6, 7 and 8, the ram unit 7 is provided, at its base 8, with a chain pull plate 70, which is shown in more detail in Figures 7 and 8. The chain pull plate 70 has a projecting cylindrical portion 72, internally threaded as at 73 to receive a projecting stud or nipple member carried by, for example, the base 8 of the ram unit, or the threaded end of the plunger 9. The threaded portion 73 of the pull plate 70 corresponds to the threaded portion 50 of the pull plate 52 shown in Figure 5.

The main body portion of the pull plate 70 is provided with oppositely extending arm portions 74 and 75, which arm portions have guide openings 76 extending therethrough, the openings 76 being for the purpose of providing guiding passages for the chain members which secure the ram in pulling position. Projecting upwardly in a direction opposite to the cylindrical portion 72 of the pull plate 70 is a boss 77, which boss defines an opening 78 out of the plane of arms 74 and 75 and extending in a direction normal to the axis of the openings 76.

In the operation of the mechanism shown in Figure 6, one of the pull plates 70 is secured to the base 8 of the ram unit 7 by means of a coupling member or the like, while the other pull plate 70 is secured to the threaded head of the axially movable plunger 9 carried by the ram unit. A chain member 79 has the intermediate portion thereof extending through the opening 78 of the pull plate 70 carried by the plunger, as shown at 80, and the two extending ends of the chain member 79 pass through the guide openings 76 of the pull plate connected to the base of the ram unit, one end of the chain being provided with a hook member 82 adapted to engage in and secure any suitable link of the opposite end 83 of the chain 79, whereby the chain may be adjustably hooked about any suitable member to be bent or straightened, such as the member 84. By the provision of the hook 82, it is apparent that the chain 79 may be carried by the ram unit, as the ram unit is moved into various positions, and all that is required to connect it to the member to be operated upon is to hook the hook 82 in the desired link of the end 83 of the chain 79, whereby the ram unit is adjustably secured in proper position with respect to the member 84.

Similarly, a corresponding chain member 85 has the intermediate portion 86 thereof passing through the opening 78 in the pull plate 70 carried by the base of the ram unit, while the extending ends 87 and 88 of the chain unit pass through corresponding guide openings 76 in the pull plate secured to the plunger head, and are secured about suitable supporting members, such as the members 89, by means of suitable hooks 90, looping about the members 89 and being then engaged in any desired one of the links forming the ends 87 and 88 of the chain 85.

It is obvious that, if desired, the chain 85 may be provided with only a single hook member 90, so that it may be hooked about a support in the same manner in which the chain 79 is secured, if desired. By merely unhooking the hooks 82 and 90, the ram unit, together with the chains, may be placed in any desired position, the chains being engaged in the bosses 77 and threaded through the openings 76 so that a minimum of

time is required for connecting the unit in position.

The operation of the mechanism shown in Figure 6 is similar to that described in connection with Figure 3, the application of pressure through the conduit 20 to the ram unit 7 causing extension of the plunger 9, which in turn produces a tension pull upon the chain 79, and a corresponding thrust against the base of the ram unit, producing a tension pull upon the chain 85. As a result, the plates 70 tend to move away from each other, and thus tend to draw the secured ends 82, 83 of the chain 79 and the ends 87, 88 of the chain 85 toward each other, thereby producing a pulling stress upon the members 84 and 89, which pulling stress can be regulated as desired by the operator, by means of the indications produced by the graduations on the annular surface of the plunger 9, and the pressure being applied to the unit through the conduit 20.

It is therefore believed apparent that we have provided a ram pulling mechanism capable of producing a bending or straightening of any desired metal members with the maximum amount of force per unit of pressure applied to the unit, and in which the pulling force is exerted in a line substantially in the direction of desired pull. The unit is capable of rapid adjustment and connection between variously spaced members, facilitating its use for a large number of operations, and is capable of self-alignment between two spaced members whenever force is applied thereto.

It is obvious that if the chains 55 and 56 of the unit shown in Figure 3 were removed, the unit could be employed for pushing the members 72 and 73 apart, if such operation were desired.

While we have disclosed the ram unit as particularly applied for pulling mechanism, therefore, we do not intend to be limited to the exact operation and connection of the members as shown and described, but only in so far as defined by the scope and spirit of the appended claims.

We claim:

1. In a mechanism of the class described comprising a power unit including an axially movable plunger, separate means carried by said plunger and at the opposite end of said unit for receiving separate chain members, each of said means including means for guiding the movement of the chain member secured to the other of said means, and a flexible conduit connected to said unit for supplying liquid under pressure thereto to move said plunger outwardly of said unit.

2. In a mechanism of the class described, a power unit, chain-pull plates at opposite ends of said unit, chain members having their intermediate portions looped about spaced metal members and having the extending ends thereof secured to said plates, and means for applying hydraulic pressure to said unit for moving said plates away from each other to produce a tension stress upon said chain members between said spaced metal members.

3. In a mechanism of the class described, a portable ram unit, pull plates at opposite ends thereof having laterally spaced latching portions, separate flexible tension members each secured to the latching portions of the pull plate at one end of said unit and extending alongside and then outwardly beyond the opposite end of said unit for connection to spaced metal members, each of said pull plates having guide means disposed normal to said latching portions for receiving said extending portions of said tension mem-

- bers, and means for expanding said unit axially to move the secured ends of said tension members away from each other whereby a tension stress is produced between said metal members.
5. 4. In a mechanism of the class described for producing a tension stress between two spaced members, a portable ram unit capable of being placed between said members, chains connected to each end of said unit and extending outwardly 10 of the opposite ends of said unit for connection to said members, and means at said opposite ends of said unit for guiding the extending portions of said chains whereby upon axial extension of said ram unit said chains automatically align 15 said unit in the direction of the tension stress between said spaced members.
5. In combination, a power unit comprising a ram cylinder and a ram plunger movable axially outwardly of said cylinder, chain plates on said 20 plunger and said cylinder, chains carried by each of said plates and passing through the other of said plates for connection to a pair of spaced members, and means for transmitting hydraulic pressure to said cylinder to expand said power 25 unit axially whereby said chains exert a pulling stress between said spaced members.
6. A chain-pull plate for a pulling mechanism of the class described having a central threaded recess, a pair of opposite disposed guide means 30 spaced from said recess, and a pair of chain-engaging lug portions disposed on opposite sides of said recess and extending normally to said guide means.
7. A chain-pull plate for a pulling mechanism 35 of the class described comprising a plate member of generally cruciform shape, a threaded recess formed centrally in said plate member for attaching said member to a power unit, a pair of chain-engaging lug means formed in one pair 40 of oppositely projecting arms of said member, the other pair of oppositely projecting arms having guide means formed therein capable of slidably receiving chain members.
8. A chain-pull plate for a pulling mechanism 45 of the class described comprising a central portion having an internally threaded recess therein, four arm portions projecting radially outwardly of said central portion, chain-engaging lug means in two of said arm portions, and chain 50 guiding means in the other two of said arm portions.
9. In a mechanism of the class described, a power unit, a pump unit for developing a hydraulic pressure, flexible fluid transmission 55 means between said units, said power unit comprising a base portion having a plate secured thereto, a chain connected to said plate and looped about a metal member, a plunger in said power unit, a plate secured to the projecting end 60 of said plunger, and a chain connected to said plate and looped about a second metal member, said plunger moving outwardly of said base portion upon transmission of pressure to said power unit for producing a tension stress upon said 65 chains between said metal members.
10. In a pulling mechanism of the class described, a power applying unit comprising a ram cylinder and an axially movable plunger, a chain-pull plate carried by said cylinder, a chain-pull 70 plate carried by said plunger, means for securing chains to said plates, said chains being looped about a pair of spaced metal members, and means at a point remote from said unit for developing a hydraulic pressure including means for transmitting said pressure to said power unit inde- 75
- pendently of stresses incident to development of said pressure whereby said plunger is moved outwardly of said ram cylinder to produce a tension stress on said chains between said members.
11. In a pulling mechanism of the class described, a ram unit comprising a ram cylinder and an axially movable plunger therein, chain-pull plates carried by said cylinder and said plunger at opposite ends of said unit, separate chains connected to each of said plates and 10 guided for movement in the other of said plates, said chains being looped about two spaced members whereby extension of said plunger outwardly of said cylinder produces a tension stress on said chains between said members tending to draw 15 said members toward each other.
12. The method of pulling two spaced members toward each other which comprises connecting chains to each of said members, movably supporting the end of each chain with the adjacent 20 portion of the other chain in overlapped position between said members, and spreading the supported ends of said chains apart to exert a straight line pulling stress between said spaced members to reduce the spacing between said 25 members.
13. The method of producing a pulling stress between two spaced members which comprises securing tension means to said members, extending the ends of said means into the space between 30 said members in overlapping relation, connecting the extending portions of said means to opposite ends of a power unit so that the tension means from one of said spaced members extends alongside said power unit and is connected to the 35 far end thereof, the other tension means extending from the other spaced member alongside said power unit and being connected with the opposite end of the latter, and hydraulically expanding said unit to separate said ends and pull the 40 portions of said tension means engaging said members toward each other.
14. The method of producing a pulling stress between two spaced members which comprises wrapping chains about said members, extending 45 the ends of said chains into the space between said members, connecting the extending portions of said chains to opposite ends of a power unit, developing a hydraulic pressure at a point remote from said members, transmitting said pressure to said unit independently of stresses developed at said remote point, and hydraulically expanding said unit by said pressure to pull the portions of said chains engaging said members 50 toward each other.
15. In combination, a power unit comprising a ram cylinder and an axially movable ram plunger therein, a plate secured to the base of said cylinder, a pair of rod members carried by said plate and extending along opposite sides of said cylinder past the opposite end thereof, a second plate secured across the extending ends of said rods, a third plate slidably mounted on said rods intermediate the cylinder and the ends of said rods and secured to said plunger, chain means 55 wrapped around a metal member and connected to said second plate, chain means wrapped around a second metal member and secured to said third plate, said power unit being placed between said metal members, and means for hydraulically moving said plunger outwardly of said cylinder to move said second and third plate members toward each other for producing a pulling 60 stress on said chain means.
16. In combination, a power unit comprising a 70

ram cylinder and an axially movable ram plunger therein, a plate secured to the base of said cylinder, a pair of rod members carried by said plate and extending along opposite sides of said cylinder past the opposite end thereof, a second plate secured across the extending ends of said rods, a third plate slidably mounted on said rods intermediate the cylinder and the ends of said rods and secured to said plunger, chain means wrapped around a metal member and adjustably connected to said second plate, chain means wrapped around a second metal member and adjustably secured to said third plate, said power unit being placed between said metal members, means remote from said unit for developing a hydraulic pressure, flexible conduit means for transmitting said pressure to said ram cylinder for hydraulically moving said plunger outwardly of said cylinder to move said second and third plate members toward each other for producing a pulling stress on said chain means.

17. In a pulling mechanism of the class described, a ram unit having an axially movable plunger, pull plates at opposite ends of said unit, chains carried by each of said pull plates and guided for movement through the opposite pull plate, and means at the extending ends of said chains for securing them to metal members spaced away from opposite ends of said unit.

18. A chain pull plate comprising a central portion having an internally threaded recess therein, a pair of oppositely extending arm portions having guide openings therethrough, and an intermediate axially projecting boss portion opposite said recess having an opening extending therethrough normal to the axes of said guide openings and intermediate said arm portions.

19. The method of pulling two spaced members toward each other which comprises connecting flexible tension members to each of said spaced members, overlapping the ends of said flexible members, applying a separating force to the spaced apart ends of the overlapped portions of said flexible members in alignment with the latter so as to force the overlapped ends of said tension members apart to exert a pulling stress between said spaced members, and supporting the force applying means on said flexible tension members at points spaced around the ends thereof.

20. In a pulling mechanism of the class described, a ram unit having an axially movable plunger, a plate member secured to the base of said unit, a second plate member carried by said movable plunger, there being openings formed in said second plate member, tension transmitting means carried by said second plate member and extending alongside said ram unit and adjacent said first plate member, and tension means connected with said first plate member and extending alongside said unit in a direction opposite to said first mentioned tension means outwardly of the unit through the openings in said second mentioned plate member.

21. In a mechanism of the class described, a power unit, pull plates at opposite ends of said unit, flexible tension members having their outer end portions connected with spaced metal mem-

bers and having their inner ends extending in overlapped relation and secured, respectively, to the furthest pull plate, and means for applying hydraulic pressure to said unit for moving said plates away from each other to produce a tension stress upon said flexible members between said spaced metal members for pulling the latter toward each other.

22. A pull mechanism for producing a tension stress between two spaced members comprising a first device for developing a hydraulic pressure directly under the control of the operator; a second device mechanically disassociated from said first device and operable in any desired angular position for producing a straight line force, means coupling said members in overlapped relation to opposite ends of said second device; and a third device comprising a flexible pressure transmitting member connecting said other two devices and transmitting pressure from said first device to said second device independently of stresses produced by development of said pressure at said first device.

23. The method of pulling two spaced members toward each other which comprises engaging each of said members by a flexible tension member, overlapping the free portion of said tension members, connecting said overlapped portion to the opposite ends of expandable means, supporting said means in position between said spaced members in the line of stress therebetween on portions of said tension members intermediate said spacing members and the points of connection of said tension members to said means while providing free movement of said intermediate portions of said tension members with respect to said means, and expanding said means to pull the engaged portions of said tension members toward each other.

24. In an assembly for pulling two spaced members toward each other including a ram unit comprising a cylinder and an axially extensible piston carried thereby and having pull plates secured to the base of said cylinder and to the outer end of said piston, the method of producing a tension stress between said members which comprises engaging each of said members by flexible tension means, connecting each tension means to opposite sides of the pull plate disposed remote from the member with which the tension means is engaged with the intermediate portions of said tension means in overlapped position along the sides of said unit, guiding said intermediate portions of said tension means for movement relative to said unit on the ends of said unit adjacent the member with which each of said tension means is engaged to thereby support said unit on said tension means in line with the direction of stress, and applying pressure from a remote source to said unit to spread said pull plates apart to thereby exert a uniform tension stress on said tension means through said opposite sides of said plates to which said tension means are connected.
